(57) **CLAIM**
I claim the ornamental design for a lockbox cover, as shown and described.

DESCRIPTION

FIG. 1 is a perspective view of a lockbox cover, showing a first embodiment of my new design in a deployed configuration; FIG. 2 is a front elevational view of FIG. 1; FIG. 3 is a left-side elevational view of FIG. 1; FIG. 4 is a rear elevational view of FIG. 1; FIG. 5 is a right-side elevational view of FIG. 1; FIG. 6 is a top plan view of FIG. 1; FIG. 7 is a bottom plan view of FIG. 1; FIG. 8 is a perspective view of the first embodiment, illustrated in a flat configuration; FIG. 9 is a right-side elevational view of a second embodiment thereof in the deployed configuration; FIG. 10 is a bottom plan view of FIG. 9; FIG. 11 is a top plan view of the second embodiment in the flat configuration; and, FIG. 12 is a bottom plan view of FIG. 11. The broken lines showing a lockbox in FIG. 1 depict environmental matter and form no part of the claimed design.
